(57) **CLAIM**

The ornamental design for a puzzle table as shown and described.

DESCRIPTION

FIG. 1 is a front, left and top perspective view of a puzzle table, showing my new design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 2.

FIG. 12 is an enlarged view of detail 12 in FIG. 2.

FIG. 13 is another front, left and top perspective view of the puzzle table in an alternate configuration of use with the drawers removed; and,

FIG. 14 is another front, left and top perspective view of the puzzle table in a second alternate configuration of use.

The dashed broken lines depict portions of the puzzle table that form no part of the claimed design. The dot-dash broken lines surrounding details shown in FIGS. 1, 2 and 9-12 are for purposes of annotating the enlarged views only and form no part of the claimed design.
